CONTROL FOR AIRPLANES

Charles R. Jamison, Morgantown, W. Va.

Application October 26, 1945, Serial No. 624,709

5 Claims. (Cl. 244—83)

1

This invention relates generally to improvements in airplanes and pertains particularly to an improved control mechanism therefor.

A principal object of the present invention is the provision of a universal control mechanism which is so constructed that the operator may effectually control the rudder, the elevators, and the ailerons by the manipulation of a single movable unit or structure, with the hands alone, thus doing away with the necessity of using the feet for manipulating any of the control elements, as is necessary in connection with the operation of control mechanism of the type at present in use.

Another object of the invention is to provide an airplane control mechanism which is operated solely by the use of the hands and by the shifting or manipulation of a single structure, and which is so designed as to be strong and durable and at the same time free of complicated parts which might easily get out of order and require frequent attention as to repairs and adjustments.

Still another object of the invention is to provide a control mechanism for airplanes which embodies a single control stick and a wheel mounted thereon, by means of which the hands of the pilot may be used for effecting the manipulation of all of the different control elements of the plane which are employed for governing the direction of movement of the same.

A still further object of the invention is to provide a unitary control mechanism of the character above stated in which a hand steering wheel is mounted upon an arm pivotally supported upon the control stick so that the wheel may be shifted or swung over from operating position in front of one pilot's seat to operating position in front of an adjacent pilot's seat, the control stick or shaft upon which the hand wheel is supported, being disposed in a plane passing between the seats.

Other objects and advantages of the invention will become apparent as the description of the same proceeds and the invention will be best understood from a consideration of the following detailed description taken with the accompanying drawings forming a part of this application, with the understanding, however, that minor changes may be made in the structure so long as such changes do not depart materially from the salient features of the invention as expressed in the appended claims.

In the drawings:

Figure 1 is a view in dotted outline of an airplane in side elevation showing the placement

2

therein of the control mechanism of the present invention.

Figure 2 is a view in perspective of the control mechanism.

Figure 3 is a view showing, partly in elevation and partly in section, the control stick and parts immediately adjacent thereto.

Figure 4 is a sectional view taken substantially on the line 4—4 of Figure 3.

Figure 5 is a sectional view taken substantially on the line 5—5 of Figure 3.

Referring now more particularly to the drawings there is illustrated in Figure 1, in a conventional manner, one type of airplane in which the present control mechanism may be mounted. In this figure the body or fuselage is generally designated 10 and at the rear end of the body is the usual rudder 11 and the pair of elevators 12, one only of which is shown. The numeral 13 generally designates the wing, at the rear or trailing edge of which is pivotally mounted the aileron 14. One pilot's seat is shown and designated 15 and the control mechanism of the present invention is mounted in a position relative to the pilots' seats so that a pilot in either seat will be able to conveniently operate the several movable parts of the plane structure by means of which the direction of movement of the structure is controlled.

In accordance with the present invention there are provided suitable bearing brackets or bearing units 16 which are mounted adjacent to opposite sides of the fuselage structure forwardly of the pilots' seats and upon any suitable part of the airplane frame.

In each of the bearing brackets 16 there is rotatably mounted one end of a tubular trunnion 17, these trunnions being aligned transversely of the structure as illustrated in Figure 2.

Located between and connecting the spaced opposed inner ends of the tubular trunnions 17 is a relatively flat wheel housing 18, the opposite vertical edges of which are provided with the outwardly directed nipples 19, in each of which the adjacent end of a trunnion 17 is fixed. Thus it will be seen that the housing 18 and the trunnions 17 are joined together as a unit and are oscillatable on an axis extending transversely of the plane.

Mounted within the housing 18 for rotation upon the pivot 20, is a pulley wheel 21, with which is integrally formed or connected in a suitable manner, the gear pinion 22. As shown the lower part of the housing 18 extends below the trunnions 17 and the pivot 20 for the pulley wheel 21 is placed below the axial center of oscillation

for the housing and trunnions, so that the periphery of the pulley wheel at the top thereof will be substantially in line with the center of oscillation for the trunnions.

Above the pivot 20 there is rotatably supported within the housing, between the front and rear walls, the pivot pin 23. The rotary centers for the pivots 20 and 23 are parallel and lie in a plane extending lengthwise of the center of the plane body.

The top part of the wheel housing 18 is provided with the slot or opening 24 and extending from within the housing upwardly through this opening 24 is the shank portion 25 of a gear segment 26. The pivot 23 passes through the radial center of this gear segment and the teeth 27 thereof have toothed engagement with the gear pinion 22 so that upon oscillation of the gear segment on the pivot 23 turning movement will be imparted to the pulley wheel 21.

The body portion of the gear segment and the shank thereof are of hollow form and disposed within the hollow portion of the gear segment is a pulley wheel 28 which is freely rotatable upon the pivot 23 so that it may be turned on the pivot without necessitating the oscillation of the gear segment.

The upper or outer end of the gear segment shank 25 has secured therein the tubular column 29 which normally stands vertically and carries upon its upper end the hollow head 30.

Within the head 30 is located the sprocket gears 31 which are coupled together and pivotally supported upon the pivot pin or axle 32 which extends transversely of the head. This pivot axle is parallel with the pivots 23 and extending over one of the sprocket gears 31 and downwardly through the tubular column 29 into the hollow portion of the gear segment 26, is a sprocket chain 33 which passes around the sprocket gear 34 which is joined concentrically to the pulley wheel 28.

Pivotally supported upon the head 30 for oscillation around the axis of the pivot pin 32 is the short column extension housing 35. This housing is coupled at one end with the head 30 to swing around the pivot 32 as shown and in its outer or free end is pivotally supported the shaft 36 upon which is carried, within the extension housing, the sprocket wheel or gear 37 while one end of the shaft 36 which extends outside the extension housing and rearwardly therefrom, carries the steering wheel 38.

Extending through the extension housing 35 is the sprocket chain 39 which connects together the gear 37 and one of the gears 31. By this means it will be seen that rotation of the hand wheel 38 will impart rotary movement to the pulley wheel 28 which wheel is connected with and controls the operation of the airplane rudders as hereinafter described.

At each side of the wheel housing 18, each trunnion 17 has formed therein the rearwardly directed slots 40 and extending vertically through the trunnion and across the central part of each slot 40 is the pivot pin 41, the ends of which are suitably mounted in the walls of the trunnions. Each pivot pin 41 carries a pulley wheel 42 and the pivots for these pulley wheels are so positioned that the periphery of the pulley wheel thereon has the center line or axis line of the trunnion passing tangentially thereacross.

Attached to the pulley wheel 28 are rudder actuating cables 43, each of which passes from the lower edge of the pulley wheel into one trun-

nion 17 and around a pulley 42 outwardly through the adjacent opening 40 and toward the rear of the airplane for connection with the rudder 11. These rudder cables 43 pass partly around a pulley 28 and are secured thereto so that rotation of the pulley will impart positive movement to one cable to effect swinging of the rudder in one direction and such swinging of the rudder will impart positive movement to the other cable to take up slack therein as it is released from the pulley.

Outwardly from each of the pulleys 42, each trunnion 17 has extending transversely therethrough and pivotally supported therein, a pulley wheel pivot pin 44 upon which is mounted a pulley wheel 45. At each pulley wheel 45 the trunnion 17 in which the wheel is housed, is slotted as indicated at 46 for the passage outwardly of an aileron control or actuating cable 47, which passes around the pulley 45 and axially through the trunnion to the wheel housing 18 and to the periphery of the pulley wheel 21, to which it is secured.

It will be readily apparent when the pulley wheel 21 is turned one of the aileron cables 47 will be wound up thereon and the other one will be unwound or payed out. This rotation of the pulley wheel 21 for the operation of the ailerons is effected by oscillating the column or standard 29 transversely of the ship, that is, either to the right or to the left of the pilot.

As previously stated the trunnions 17 are mounted for turning movement in the bearings 16. Thus the trunnions and the housing 18 may be turned on an axis extending transversely of the ship, by oscillating the standard or column 29 forwardly or rearwardly. This action is employed for the control of the elevators 12, and such control is had through the medium of the crank arm 48 which is secured to a trunnion 17 and hangs downwardly therefrom. Such crank arm is connected at its lower end with the actuating rod 49 which in turn is connected with the crank 50 which is attached to the pair of oppositely extending arms 51. From the outer end of each of these arms a cable 52 is extended to an elevator.

It will be readily apparent that the standard 29 takes the place of the usual control stick and that such standard may be oscillated in either direction from the vertical transversely of the plane or in either direction from the vertical forwardly and rearwardly of the plane to effect the actuation of the aileron and elevator cables and the elements to which they are attached. By turning the hand wheel 38 the rudder mechanism is effectively controlled. Thus it will be seen that when a pilot is using the mechanism herein described he can readily shift or move the rudders, ailerons or elevators entirely from the hand wheel 38 and that no supplemental operating elements, designed to be controlled by the feet, are required.

In order to prevent the swinging of the column 29 too far in either direction on the pivot 23, adjustable spring stops are provided in the opposite sides or side edges of the housing. These stops each comprises an adjustable pin or screw 53 threaded through the side edge wall of the housing to the interior thereof and directed at its inner end toward the adjacent side of the gear segment 26. Between the inner end of each pin 53 and the adjacent side of the gear segment, is a relatively or stiff spring 54 which constitutes a separating means between the adjacent side of

the gear segment and the pin with which it is connected.

As will be readily apparent the tension of the springs 54 against the sides of the gear segments may be increased or decreased by adjusting the screws or threaded pins 53 and these springs not only function to return the column 29 to vertical or upright position when it has been swung to the right or to the left but the springs with the pins 53 function to prevent the swinging of the gear segment to such an extent as to cause disconnection of the segment teeth from the teeth of the pinion gear.

I claim:

1. In an airplane having flight controlling units comprising a rudder, an elevator and ailerons, a relatively long tubular member supported upon the airplane to extend transversely thereof and for turning on its long axis, said tubular member including a housing intermediate its ends, a normally upright column having one end extended into said housing, a pivotal connection between the said one end of the column and the housing by which the column may be swung in a plane extending transversely of the airplane, turning movement being imparted to said member by swinging movement of the column in a plane extending longitudinally of the airplane, a pair of wheels rotatably supported within the housing, an operative connection between one of the wheels and the lower end of said column by which turning movement is imparted to the said one of the wheels upon swinging of the column on its pivot in the plane extending transversely of the airplane, an operative coupling between the said one of the wheels and one of the flight controlling units for the actuation of the latter upon the turning of said one of the wheels, an operative coupling between the other one of the wheels and another one of the flight controlling units for the operation of the last mentioned unit upon the turning of the said other wheel, means carried by the column for effecting the turning of the said other wheel, and an operative coupling between the said member and the third one of the flight controlling units by which the last mentioned one of the units is actuated upon turning of the member on its long axis.

2. A mechanism of the character stated in claim 1, in which the said means coupling the lower end of the column with the said one of the wheels, comprises a gear segment connected with said column and disposed within the housing, and a pinion connected concentrically with the said one of the wheels and having toothed connection with said segment.

3. A mechanism of the character stated in claim 1, in which the said means carried by the column for imparting rotary motion to the other one of the wheels comprises a relatively long hollow extension housing pivotally connected at one end with the other end of the column for swinging in a vertical plane on a pivot parallel to the pivotal axis on which the column swings transversely of

the airplane, a hand wheel pivotally supported upon the other end of the extension housing for turning on an axis paralleling the axis upon which the first mentioned end of the housing turns, and an operative driving connection between the hand wheel and the said other one of the wheels, said driving connection passing through the extension housing and said column.

4. In an airplane having flight controlling units comprising a rudder, an elevator and ailerons, control means for said units comprising a relatively long member supported upon and transversely of the airplane for turning on its long axis, said member including a housing, a pair of vertically spaced shafts supported within the housing with their axes extending longitudinally of the airplane, a gear segment supported upon the upper one of said shafts, a normally upright column secured to said gear segment and extending upwardly through and beyond the top of the housing, the column and gear segment being swingable upon the said upper shaft in a vertical plane extending transversely of the airplane, the column being swingable with and on the axis of the member in a vertical plane extending longitudinally of the airplane, a pulley supported upon the upper one of the shafts for rotation independently of the segment, operative connections between said pulley and one of said units for effecting actuation of the said one of the units upon turning of the pulley, means carried by the column for imparting rotary motion to the pulley, a gear pinion supported upon the lowermost shaft and having toothed connection with said segment, a pulley supported upon the lowermost shaft and connected with the pinion to turn therewith, an operative coupling between the last mentioned pulley and another one of said units, and an operative coupling between the said member and the remaining one of the units for actuating the latter upon the turning of the long member through the swinging of the column in the longitudinally extending plane.

5. Control mechanism for an airplane as stated in claim 4, with a pair of centering springs within the housing and supported upon opposite sides of said gear segment above the top shaft, between which said segment is positioned, the springs engaging opposite sides of the segment and normally functioning to maintain the segment and column in the said upright position.
